UNITED STATES PATENT OFFICE.

NILS N. EGGE, OF JOICE, IOWA.

DRAFT-EQUALIZER.

No. 808,823.

Specification of Letters Patent.

Patented Jan. 2, 1906.

Application filed January 9, 1905. Serial No. 240,267.

To all whom it may concern:

Be it known that I, NILS N. EGGE, a citizen of the United States, residing at Joice, in the county of Worth and State of Iowa, have invented a new and useful Draft-Equalizer, of which the following is a specification.

This invention relates to draft-equalizers, and is designed to provide an improved device of this character especially arranged for use in connection with plows, either gang, riding, or walking, and it is proposed to provide for adjusting the connection of the device with plow-beams or the like to accommodate the device to different numbers of draft-animals.

With these and other objects in view the present invention consists in the combination and arrangement of parts, as will be herein-after more fully described, shown in the accompanying drawings, and particularly pointed out in the appended claims, it being understood that changes in the form, proportion, size, and minor details may be made within the scope of the claims without departing from the spirit or sacrificing any of the advantages of the invention.

In the accompanying drawings, Figure 1 is a plan view of a draft-equalizing device embodying the features of the present invention. Fig. 2 is a cross-sectional view on the line 22 of Fig. 1. Fig. 3 is a detail sectional view on the line 33 of Fig. 1.

Like characters of reference designate corresponding parts in each and every figure of the drawings.

The present device includes what will be termed the "main long evener-bar" 1 and the supplemental shorter evener-bar 2. A substantially U-shaped clip or loop 3 embraces the inner end of the main evener-bar, to which it is rigidly connected in a substantially horizontal position, with the closed end portion of the loop projected at the inner end of the evener-bar, the supplemental evener-bar being pivotally connected to the extremity of the loop, as at 4. As best indicated in Fig. 3, it will be noted that upper and lower plates 5 and 6 are secured to the supplemental evener-bar 2 and projected at the inner end thereof, so as to produce a slot or bifurcation within which the projected portion of the loop 3 is received, whereby the two evener-bars are overlapped and pivotally connected, as at 4, at a point intermediate of the ends of the supplemental bar, but adjacent its inner end.

A yoke or pair of links 7 embrace the inner end portion of the evener-bar 1 and are pivot-

ally connected thereto by a suitable fastening 8, which pierces the bar in front of the longitudinal center thereof, the rear ends of the links being designed to straddle a horizontally-disposed clevis 10, carried by a plow-beam 11 and perforate to receive a fastening 12, preferably a bolt, which may be engaged with any of the seats of the clevis. A cross head or bar 13 is fulcrumed intermediate of its ends between the links 7, as indicated at 14, and has one end connected to the inner end of the supplemental bar 2 by means of a pair of links 15, which embrace the plates 5 and 6 and are pierced by a bolt or suitable fastening 16, which works in the loop 3. The opposite end of the cross-head or cross-bar 13 is provided with a rigid rearwardly-directed and horizontally-bifurcated arm 17, loosely straddling the clevis and adjustably connected thereto by a bolt or similar fastening 18. The outer ends of the two evener-bars are provided with the respective openings 19 and 20, or other suitable means may be provided for the connection of swingletrees and doubletrees with the respective evener-bars.

From the foregoing description it will be noted that the present device is entirely complete in itself and may be readily connected to a plow-beam or the like without any change in the latter, and to accommodate the device to different numbers of draft-animals the connections 12 and 18 with the plow-beam may be separated and spread according to the number and disposition of the draft-animals which are to be connected to the evener-bars.

Having fully described the invention, what is claimed is—

1. In a draft-equalizing device, the combination of a main evener-bar, a supplemental evener-bar fulcrumed thereon, a draft connection extending rearwardly from the main evener-bar independently of the supplemental evener-bar, a cross-head fulcrumed intermediate of its ends upon the draft connection, a connection between one end of the cross-head and the supplemental evener-bar, and a draft connection at the other end of the cross-head.

2. In a draft-equalizing device, the combination of a main evener-bar, a supplemental evener-bar fulcrumed intermediate of its ends upon the inner end portion of the main evener-bar, a draft connection extending rearwardly from the main evener-bar, a cross-head fulcrumed intermediate of its ends upon the draft connection, a connection between one end of the cross-head and the inner end of the

supplemental evener-bar, and a draft connection carried by the other end of the cross-head.

3. In a draft-equalizing device, the combination of pivotally-connected main and supplemental evener-bars, a draft connection extending rearwardly from and carried solely by the main bar, and another draft connection extending rearwardly from and carried solely by the supplemental bar and having a portion crossing and pivotally connected to the draft connection of the main bar.

4. In a draft-equalizing device, the combination of a main evener-bar having a transverse slot adjacent its inner end, a supplemental evener-bar having its inner end bifurcated and straddling the slotted portion of the main evener-bar, said supplemental bar being fulcrumed upon the inner extremity of the main bar, a draft connection extending rearwardly from the inner end portion of the main bar, a cross-head fulcrumed intermediate of its ends upon the draft connection, links extending between one end of the cross-head and the inner end of the supplemental bar, a pivot-pin connecting the links and the inner end of the supplemental bar and working in the slot

of the main bar, and a draft connection at the opposite end of the cross-head.

5. In a draft-equalizing device, the combination of a main evener-bar having a substantially **U**-shaped loop embracing the inner end of the bar, a supplemental bar having its inner end bifurcated and straddling the loop to which it is pivotally connected at the inner end of the bifurcation, a draft connection extending rearwardly from the inner end portion of the main bar, a cross-head fulcrumed intermediate of its ends upon the draft connection, links connected to one end of the cross-head and embracing the bifurcated inner end of the supplemental bar, a pivot-pin piercing the links and the supplemental bar and working in the loop of the main bar, and a draft connection carried by the other end of the cross-head.

In testimony that I claim the foregoing as my own I have hereto affixed my signature in the presence of two witnesses.

NILS N. EGGE.
